UNITED STATES PATENT OFFICE.

WALTER C. BROWN, OF NEVADA, IOWA.

FILLING MEANS FOR GASOLINE TANKS.

Application filed June 27, 1921. Serial No. 480,594.

To all whom it may concern:

Be it known that I, WALTER C. BROWN, a citizen of the United States of America, and resident of Nevada, Story County, Iowa, 5 have invented a new and useful Filling Means for Gasoline Tanks, of which the following is a specification.

An object of this invention is to provide an improved construction for caps or closures of the filling ports of containers such as gasoline tanks employed for storage of fuel supply on automobiles, tractors and the like.

A further object of this invention is to provide a screw member and a hinged member in combination, the hinged member forming a wicket in the screw member and being removable and replaceable with the screw member relative to a filling port of a container.

A further object of this invention is to provide means for latching the hinged member or wicket in closed position in the screw member.

25 A further object of this invention is to provide means for minimizing or preventing leakage or evaporation of the contents of the container between the screw member and wicket.

30 My invention consists in the construction, arrangement and combination of elements hereinafter set forth, pointed out in the claims and illustrated by the accompanying drawing, in which—

35 Figure 1 is an elevation of a container, showing my improved closure applied thereto, the dotted lines showing the wicket in open position. Figure 2 is a plan of the closure, showing the wicket in open position.

40 Figure 3 is a vertical section on the indicated line 3—3 of Figure 2, the wicket being partially closed. Figure 4 is a cross-section on the indicated line 4—4 of Figure 2, the wicket being in closed position.

45 In the construction and mounting of the device as shown the numeral 10 designates a socket formed with a peripheral flange 11 on its outer end and an inwardly-extending flange 12 on its inner end. The socket 10 is

50 formed with an external thread and is adapted to be screwed into an internally-threaded flanged collar 13 commonly used in fixed relation on and surrounding a filling-port in a container or tank 14. The screw threaded connection between the socket 10 and flanged collar 13 is substantially leakage and evap-

oration proof. The socket 10 is formed with a tapering inner wall surface, which is broken at diametrically opposite points by inwardly-extending lugs 15, 16, the former being formed with an upwardly-extending hinge-member 17 and the latter being formed with a step or shoulder 18 and with tapering walls. A plug or wicket 19 is constructed with a tapering outer wall surface to fit the socket 10 snugly and is hinged at one side by a pin 20 to the member 17. The plug or wicket 19 is formed with diametrically opposite notches 21, 22, having tapering walls, to embrace and fit the lugs 15, 16 respectively. The close fitting of the tapering wall surfaces of the socket and plug, and their lugs and notches, minimizes leakage or evaporation between them of the contents of the tank or container 14. A portion 23 of the plug or wicket 19 is adapted to project through the hole within the flange 12 when the wicket is in closed position and, together with said flange, supplement the tapering walls in preventing leakage and evaporation. 65 An annular peripheral flange 24 is formed on the outer edge of the plug or wicket 19 and said flange is formed with a lip 25 adjacent the notch 22 adapted to be engaged by a thumb, finger or tool to facilitate opening 70 or closing the wicket. A bent leaf spring 26 is fixed to the socket 10 and extends outwardly normally in the path of travel of a portion of the flange 24 which it is adapted to engage yieldingly to latch and hold the wicket in closed position in order that said wicket may not be jarred open in the use of a vehicle on which the container is mounted. An angular lug 27 is formed on and extends outwardly from the central portion of the 75 plug or wicket 19 and is adapted to receive a wrench which may be employed to seat or unseat the closure by screwing relative to the flanged collar 13.

80 For ordinary purposes of measuring the depth of contents such as gasoline in the container or for filling the same, the wicket or plug may be placed in open position; but where greater capacity of filling port is required the entire closure may be removed by unscrewing it from the collar 13.

I do not desire to be understood as limiting myself to the precise construction and arrangement shown as the same may be modified within the scope of the appended 110 claims without departing from my invention.

I claim as my invention—

1. In filling means for gasoline tanks the combination of a tank having a filling port and a flanged collar on said tank surrounding said port with a socket adapted to be screwed in said collar, said socket being formed with a tapering inner wall, the bore thereof having its largest diameter outside said tank, and a wicket member hinged to the screw socket and opening outwardly of the tank and also formed with a tapering outer wall mating said tapering inner wall, said wicket member being formed with a peripheral flange overlaying the wall of the socket.
2. In filling means for gasoline tanks, a screw socket formed with a tapering inner wall and also formed with lugs, a wicket member hinged to one lug and formed with a notch adapted to receive the other lug and formed with a tapering outer wall coacting with the tapering inner wall, and a latch connecting said socket and wicket member, a portion of said wicket member overlaying the wall of the socket. 20

Signed at Des Moines, in the county of Polk and State of Iowa, this 9th day of June, 1921.

WALTER C. BROWN. 25
